FLUID PRESSURE IMPULSE TIMER

Vivian Ray Bennett, Beverly Hills, Calif.

Application April 25, 1955, Serial No. 35,647

Term of patent 7 years

(Cl. D52—1)

FIG. 1

FIG. 2

FIG. 3

Figure 1 is a perspective view of a fluid pressure impulse timer, showing my new design;

Figure 2 is a side elevation of the fluid pressure impulse timer of Fig. 1, as viewed from the right in that figure.

Figure 3 is a plan view of the fluid pressure impulse timer of Figs. 1 and 2.

I claim:

The ornamental design for a fluid pressure impulse timer, substantially as shown.
